UNITED STATES PATENT OFFICE

2,021,056

CUT-OUT FOR SPARK PLUG SUPPRESSORS

John W. Fitz Gerald, Milwaukee, Wis., assignor to
 Allen-Bradley Company, Milwaukee, Wis., a
 corporation of Wisconsin

Application December 8, 1933, Serial No. 701,422

3 Claims. (Cl. 250—14)

This invention relates to improvements in spark plug suppressors and has as an object to provide means for short-circuiting the suppressors.

5 The discharge of the spark plugs of an automobile produces high frequency oscillations disturbing to radio reception, and these objectionable oscillations must be damped out if a radio installation in the automobile is to be successful. 10 At the present time, it is the practice to equip the spark plugs with suppressors to damp out these objectionable oscillations. These suppressors are in the form of resistors having a high electrical resistance. It has been found that this 15 high resistance in series with the spark plugs makes starting of the engine difficult in cold weather, and it is to obviate this difficulty that the present invention contemplates the provision of means to short-circuit the suppressors either 20 during only the starting cycle or whenever the ambient temperature of the engine drops below a predetermined minimum.

This general object may be attained in different ways, but it is preferable to provide each suppressor with an individual bridging member arranged to electrically bridge the terminals of the suppressor.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated two complete examples of the physical embodiment of my invention constructed according to the best modes I have so far devised for the practical application of the principles thereof, and in which:

Figure 1 is a side view of a suppressor equipped with one form of short-circuiting means;

Figure 2 is a diagrammatic illustration of a conventional ignition system illustrating the application of this invention thereto;

Figure 3 is a side view showing a modified form of short circuiting means in which the functioning thereof is in response to temperature changes;

Figure 4 illustrates another modified embodiment of the invention, wherein the blast of air induced by the fan of the engine is utilized to actuate the bridging member;

Figure 5 illustrates another manner of actuating the bridging member;

Figure 6 is a top view of an internal combustion engine illustrating the application of a number of suppressors equipped with bridging mem-

bers and common means to actuate all of the bridging members;

Figure 7 is a fragmentary view similar to Figure 6, showing a specific manner of moving the common actuating means; and

Figure 8 is a section view through Figure 6 on the plane of the line 8—8.

Referring now more particularly to the accompanying drawings in which like numerals indicate like parts throughout the several views, and especially to Figure 2, the numeral 5 designates the spark plugs of an internal combustion engine, to which current is conducted through an ignition system including a distributor 6 and a transformer 7 supplied with current from a battery 8. 15 Interposed in the leads 9 which run from the distributor to the individual spark plugs, are suppressors 10 of any conventional construction. A suppressor is also interposed in the lead to the distributor arm.

The specific construction of the suppressor forms no part of this invention and any conventional type may be employed. Generally these suppressors comprise a self-supporting resistance element (not shown), contained within a protecting body 11 having terminals 12 at its opposite ends. One of the terminals is provided with some form of mounting bracket 13 by which the suppressor may be mounted on and electrically connected with the terminal of the spark plug. The other terminal of the suppressor has means 14 for connecting the spark plug lead 9 thereto.

Normally the presence of the high resistance in series with the spark plugs does not affect the operation of the engine, but during extremely cold 35 weather, this high resistance makes starting of the engine difficult. To overcome this objection, the present invention provides simple but efficient means for short circuiting the resistance element by electrically connecting the terminals of the 40 suppressors through a bridging member indicated generally by the numeral 16.

In Figure 1, the bridging member 16 consists of a strip of bi-metallic metal 17 having one end 18 secured to one terminal by the attaching means 45 14 and its other end 19 arranged to contact the other terminal 12. Normally, the bi-metallic strip 17 is in a position at which its end 19 engages the adjacent terminal 12, thus short-circuiting the suppressor and affording a low resistance path directly to the spark plug.

To disengage the end 19 from its terminal 12, a heater coil 20 is provided. The coil may encircle the bimetallic strip or may be mounted in close proximity thereto. It is adapted to be 55 energized simultaneously with the operation of the radio by the closing of the switch 21 which controls the supply of current from the battery 22 to the radio. The circuit for energizing the coil 20 is apparent from the drawings.

A modification of the use of the bimetallic strip is illustrated in Figure 3. In this embodiment, a bimetallic strip 23 is looped back and forth to increase the range of movement of its free end 24 in response to temperature changes. The opposite end 25 of the strip is secured by the attaching means 14 to the adjacent terminal 12 of the suppressor, the free end 24 being arranged to move into and out of engagement with the bracket 13, which is in electrical connection with the adjacent terminal 12. In this embodiment, no external means are provided for causing the bridging member to move to and from operative position, the desired motion being obtained entirely from the inherent characteristics of the bimetallic strip. During normal temperatures, the free end 24 is spaced from the bracket 13, but when the temperature drops sufficiently low, the end 24 contacts the bracket and thus short-circuits the suppressor.

In Figure 4, the bridging member is actuated pneumatically by the blast of air induced by the fan 26 of the engine. For this purpose, the bridging member is in the form of a metal strip 27 having one end 28 attached to the terminal 12 at the mounting bracket 13. Opposite the other terminal the strip carries a contact point 29 to engage said other terminal. The inherent resiliency of the strip 27 normally holds the contact point 29 in engagement with the adjacent terminal.

Above the contact point 29, the strip carries a vane 30, which is in the direct path of the blast of air emanating from the fan so that when the engine attains an operating speed, the bridging member will be moved to an inoperative position.

In Figure 5, the bridging member is similar to that illustrated in Figure 1, except that it is not formed of a bi-metallic metal, but is preferably constructed of iron or steel. In its normal position, the bridging member has its free end disengaged from the adjacent suppressor terminal, and to engage the same and effect the short-circuiting of the suppressor, an electromagnet 31 is mounted on the suppressor. The electromagnet is arranged to be energized simultaneously with the closing of the starter switch 32 as is clearly evident from the drawings. Consequently, during the starting cycle, the suppressor is short-circuited.

Figure 6 illustrates a plurality of suppressors arranged in a row and supported by their respective spark plugs. Each of these suppressors is equipped with a bridging member 33 in the form of a metal strip similar to that illustrated in Figure 5, having one end anchored to one of the suppressor terminals and its other end arranged to contact the other terminal.

The normal resiliency of the bridging members 33 holds them in their operative short-circuiting positions, and to move the same out of their short-circuiting positions, the shifter rod 34 is provided. The rod 34 is slidably mounted by brackets 35 to traverse all of the suppressors and is equipped with a plurality of cams 36, one for each suppressor, which upon longitudinal shifting of the rod in one direction, moves all of the bridging members to their inoperative positions. The shifter rod 34 may be actuated manually or automatically.

If desired, the rod may be actuated by means of an electromagnet 37 as shown in Figure 7. The electromagnet 37, like the electromagnet 31, in Figure 5, is arranged to be energized simultaneously with the closing of the starting switch 32. In this form of the invention, the cams are reversed from the positions shown in Figure 6, so that upon automatic actuation of the shifter rod by the electromagnet, the bridging members are allowed to drop to their operative positions. A tension spring 38 is provided to return the rod to its position holding the bridging members in their inactive positions.

From the foregoing description taken in connection with the accompanying drawings, it will be readily apparent to those skilled in the art that this invention affords simple means for obviating the difficulties of starting caused by the presence of the high resistance in the spark plug leads where a radio is installed in an automobile.

It is also readily apparent that while several different embodiments of the invention have been illustrated, and several means of actuating the bridging members to and from their operative positions are shown, the invention is susceptible to other applications.

It is noted that in certain forms of the invention, especially that embodiment illustrated in Figure 3, where the free end of the bridging member during normal operating conditions may be in a position close to the bracket 13, but still not touching the same, the effect of a spark intensifier is obtained. This is an added advantage of the invention.

What I claim as my invention is:

1. In a suppressor of the character described and comprising a high resistance element, terminals for the high resistance element and a supporting structure for the element and terminals, a bridging member electrically connected with one of the terminals and movable to and from electrical connection with the other terminal, said bridging member being thermally responsive and moving to and from its bridging position in response to temperature changes thereat whereby the short circuiting of the high resistance element thereby is determined by the ambient temperature.

2. In a suppressor of the character described and comprising a high resistance element, terminals for the high resistance element and a supporting structure for the element and terminals, a bi-metallic strip connected to one of the terminals and having a part engageable with the other terminal to electrically bridge the terminals and shunt the high resistance element, said bi-metallic strip moving in response to temperature changes thereat whereby the short circuiting of the resistance element is determined by the ambient temperature.

3. In a suppressor of the character described and comprising a high resistance element, terminals for the high resistance element and a supporting structure for the element and terminals, a bi-metallic strip having one end secured to one of the terminals and its other end overlying the other terminal and movable in response to changes in the ambient temperature to and from a position electrically bridging the terminals and short-circuiting the high resistance element.

JOHN W. FITZ GERALD.
